UNITED STATES PATENT OFFICE.

MORRIS MICHTOM, OF NEW YORK, N. Y.

DESIGN FOR A DOLL.

46,747.

Specification for Design.

Patented Dec. 8, 1914.

Application filed September 23, 1914. Serial No. 863,237. Term of patent 7 years.

To all whom it may concern:

Be it known that I, MORRIS MICHTOM, a citizen of the United States, residing at the borough of Brooklyn, in the city of New York, in the county of Kings and State of New York, have invented a new, original, and ornamental Design for Dolls, of which the following is a specification, reference being had to the accompanying drawing, forming a part thereof.

The figure is a perspective view of a doll, showing my new design.

Copies of this patent may be obtained for five cents each, by addressing the "Commissioner of Patents, Washington, D. C."

I claim;

The ornamental design for a doll, as shown.

Signed at New York, in the county of New York and State of New York, this eleventh day of September, nineteen hundred and fourteen.

MORRIS MICHTOM.
